ELECTRICAL APPARATUS

Harold Haas, Belleville, N. J., assignor to Bendix
Aviation Corporation, South Bend, Ind., a cor-
poration of Delaware

Application April 6, 1939, Serial No. 266,404

1 Claim. (Cl. 171—229)

This invention relates to electrical apparatus, and particularly to the regulation of the voltage output of a direct current generator.

Direct current generators whose capacity is sufficiently high to produce field current flow in excess of a few amperes present a problem in voltage output regulation which is not satisfactorily met by use of vibrating regulators connected in the manner that has become standard in automotive vehicle installations which—until a very recent date—did not involve generator loads in excess of, say, fifty amperes, or voltage outputs in excess of fifteen to thirty volts.

Recent developments in the automotive field, particularly in the design of buses, aircraft and marine craft to transport heavier loads under power developed by internal combustion engines, have involved constantly increasing demands for generation of more electrical power by use of engine-driven generators of higher capacities than heretofore. The result has been to create a problem in satisfactory voltage regulation.

It is accordingly an object of the present invention to provide, in a generator system including a voltage regulator of the vibratory type, novel means for protecting the vibratory contacts against exposure to the full current capacity of the generator field, the strength of which said contacts are adapted to regulate.

Another object is to provide this protection of the contacts against exposure to currents of high amperage by a method, and by use of means, which lengthens the life of the contacts without at the same time sacrificing anything in the matter of efficiency of the voltage regulating action, as compared with that of similar vibratory regulators heretofore employed.

These and other objects of the invention will become apparent from inspection of the following specification when read with reference to the accompanying drawing wherein is illustrated the preferred embodiment of the invention. It is to be expressly understood, however, that the drawing is for the purpose of illustration only, and are not designed as a definition of the limits of the invention, reference being had to the appended claim for this purpose.

In the drawing reference characters 5 and 6 designate the armature and shunt field windings, respectively, of a direct current generator to supply current to devices (not shown) by way of positive and negative feeds 7 and 8, respectively, across which feeds are tapped the windings 9 and 10 of a vibratory armature type of voltage regulator, the vibratory armature 11 being shown

as having its contact point 12 biased to the circuit closing position by spring means 13. A third winding 14, responsive to line current and operating to modify the frequency of vibration of armature 11, may or may not be included in the voltage regulator assembly, as desired. On each opening of the vibrating contact 12 the resistance 16 is effective in the conventional manner to vary the strength of the shunt field and thereby tend to restore the predetermined voltage across the lines 7, 8; but injury to or excessive wear upon the contacts 12 is prevented by limiting current flow to said contacts in the novel manner now to be described.

A relay 21 has its winding interposed in the circuit to generator field 6, and its armature 22 provided with a contact biased away from a fixed contact 23 by spring means 24, but movable to engage said contact 23 whenever the current in field circuit 6 exceeds the predetermined value, as regulable by the tensioning of spring 24—it being understood that armature 22 is in the magnetic field of coil 21. The closing of contacts 22, 23 thus diverts from regulator contacts 12 (and intervening connections 11, 19, 21) all field current in excess of that which is considered safe for the contacts 12 to handle without undue erosion. If desired, a condenser 31 and resistor 32 may be connected in shunt with contacts 22, 23 to reduce arcing across the latter.

From the foregoing it will be understood that when the generator is started the contacts of the auxiliary field regulator 21 close and remain closed as long as the field current is heavy; but, as the field current now has a direct path to the windings 6 (by way of contacts 22, 23) the tendency will be for less current to flow in the path 12, 11, 19, 21. Consequently the resultant weakening of the field about relay 21 will permit spring 24 to re-open the contacts 22, 23; whereupon the current flow through winding of relay 21 will again increase and cause a repetition of the cycle. The result is a vibratory action of the armature of relay 21, at a frequency which is sufficient to hold the current flow through the voltage regulator circuit to a reasonably low value, and thus avoiding excessive erosion of the contacts at 12. Meanwhile the voltage regulator armature 11 continues to vibrate and control the generator voltage, in the conventional manner.

What I claim is:

In a generator system including armature and shunt field windings, a resistance element, and a vibratory type of voltage regulator having a winding connected across the armature terminals

and a contact in series with said shunt field winding and movable to alternately cut said resistance element in and out of the shunt field circuit in accordance with voltage changes across
5 said armature terminals, means for diverting from said regulator contacts that portion of the field circuit current which exceeds a predetermined value, in amperes, said diverting means including a relay having a winding forming part
10 of said shunt field circuit and interposed in said circuit between said voltage regulator contact

and in series with the shunt field winding, and also having its armature in parallel relation to said regulator contacts, to shunt the generator shunt field current from the latter whenever said current is sufficiently high to move said armature 5 to current shunting position, and means of pre-adjusted strength to yieldably oppose movement of said relay armature to the current shunting position.

HAROLD HAAS. 10
